(57) **CLAIM**

The ornamental design for a shaving razor handle as shown and described.

DESCRIPTION

FIG. 1 is a front perspective view of a design of a shaving razor handle in a first position showing my new design; FIG. 2 is a front view in the first position thereof; FIG. 3 is a rear view in the first position thereof; FIG. 4 is a right side view in the first position thereof; FIG. 5 is a left side view in the first position thereof; FIG. 6 is a top view in the first position thereof; FIG. 7 is a bottom view in the first position thereof; FIG. 8 is rear perspective view in the first position thereof; FIG. 9 is a front perspective view in a second position thereof; FIG. 10 is a front view in the second position thereof; FIG. 11 is a rear view in the second position thereof; FIG. 12 is a right side view in the second position thereof; FIG. 13 is a left side view in the second position thereof; FIG. 14 is a top view in the second position thereof; FIG. 15 is a bottom view in the second position thereof; and, FIG. 16 is rear perspective view in the second position thereof.

The dashed lines of the razor head illustrate the environment of the handle and form no part of the claimed design. The dashed lines shown on the body of the handle illustrate portions of the article and form no part of the claimed design. The dash dot broken lines illustrate the boundary of the article and form no part of the claimed design.
